TOILET

James F. Molloy, Oakland, Calif.

Application August 26, 1948, Serial No. 46,337

4 Claims. (Cl. 4-69)

This invention relates to improvements in toilets and more particularly to the flushing outlets thereof.

Among the objects of the invention is to simplify the structure of the bowl and the outlet therefrom of non-siphoning toilets.

Another object is the elimination of noise in the flushing cycle of toilets.

Another object is to increase the velocity of the outgoing water and reduce the tendency to accumulate organic matter on the wall surface of the outlet.

A further object is the avoidance of the tendency of toilet flushes to suck air into the outlet during the flushing cycle.

Flushing toilets fall into two general classes, the more common type depending upon the siphon principle to exhaust the contents of the bowl. Another type accelerates the out flow by a water jet action into the outlet. Because of the relatively large internal diameter of the outlet necessary for the passage of fecal and other matter disposed of therethrough, the outflow results in a siphonic action causing an aspirating suction drawing in air with a noisy discharge of the contents of the bowl, especially in the last stage of the outflow. When the jet action is added to the siphonic type the noise of the jet is added to the noise of the siphonic flow.

Various attempts, in the form of retarding means in the final or gravity flow of the outlet, have been made to reduce the incidental noise. But the negative action of the siphon is still present with its many disadvantages.

The present invention acts positively, in contrast to the negative siphonic action, and no aeration of the outflow of water results, because of the maintained density and centrifugal action of the discharge passage; in contrast to the usual inverted U shape of the siphon and jet types of flushers.

Other objects and advantages will appear as the description progresses. In the specification and the accompanying drawings the invention is disclosed in its preferred form. But it is to be understood that it is not limited to this form; because it may be embodied in modifications within the spirit of the invention as defined in the claims following the description.

In the one sheet of drawings:

Fig. 1 is a vertical section on the line I—I Fig. 2, of a toilet constructed in accordance with this invention.

Fig. 2 is a horizontal sectional detail of the discharge trap of the same.

Fig. 3 is a detail in side elevation, partially in vertical section, showing a modified structure of the outlet helix.

In detail the structure shown in Fig. 1, comprises the bowl 1, having the integral base 2 resting upon the floor. The upper edge of the bowl has the hollow duct 3 connected with the inlet pipe 4. From the inlet pipe the incoming water spreads out and enters the duct 3, from which it escapes through the jets such as 5 interspersed around the duct and discharging down the inner wall of the bowl.

The rear portion of the bowl has the integral cylindrical trap chamber 6, into which the contents of the bowl are discharged through the tangential outlet 7. The bottom of the chamber has the central outlet neck 8 extending into and sealed to the soil pipe 9, which is connected with the sewer in the usual manner. This chamber is closed at the top by the gasket sealed transparent cover 10.

The accelerating helix block 11, preferably composed of a yielding compound, such as rubber or a suitable plastic, snugly fits within the trap 6 and seals against the inner wall where it contacts the wall and the bottom of the trap chamber 6. It has the tangential inlet 12 alined with the outlet 7 from the bowl 1. This inlet 12 continues upward as a helical groove 13 in the perimeter 30 of the helix block. This groove is sealed by the surrounding wall of the trap 6, until it reaches the top of the block, where it discharges into the flared opening 14 of the vertical discharge outlet 15.

The water level 16 in the bowl supplied through the service pipe 17 includes the greater portion of the helical groove 13 and traps off any gases that may rise from the sewer 9 into the upper portion of the sealed chamber 6.

Before removing the cover 10, the inlet pipe 4 is disconnected from the tank and the bowl. The cover is then removed through the side door 19 permitting access to the helix block 11 for inspection or removal from the trap chamber 6, without disturbing the installation of the bowl and its sewer connections.

This invention operates substantially as follows: When the water is released from the water tank 17 or other source, in the usual manner, it rushes through the inlet pipe 4 and jets through the openings 5 into the bowl 1. The weight of this sudden volume of water causes the water to rush from the bowl through the tangential outlet 7 into the groove 13 of the helix at considerable velocity, carrying with it the contents of the

bowl. Rising through the helix groove the former contents of the bowl, represented by the water level 16, passes downwardly through the discharge passage 15 and into the sewer. The water level 16 is then restored by fresh water from the tank 17 in the final stage of the flushing cycle.

The side portion of the housing 18 has an opening closed and sealed by the door 19. This opening provides means for inspection, removal or replacement of the block 11.

A particular advantage of the present structure, is the omission of the complicated inverted U trap in the usual siphon types of bowls, with the incidental disadvantages described above.

The admission of the volume of water during the flushing cycle, which must escape through the tangential outlet 7, causes an acceleration of the flow through the helical groove 13. This creates a centrifugal action around the groove which maintains the density of the water, preventing aspiration of air that would aerate the water and create sucking and gurgling noises, so common to many of the present forms of toilets. This acceleration of flow also increases the scouring action of the flowing water, preventing the accumulation of fecal matter on the surface of the block 11 and the interior of the trap chamber 6.

The water spread laterally by the centrifugal action at the top of the block 11, decelerates the flow downward through the discharge opening 15, breaking any noisy siphoning effect at this point. The plastic nature of the block 11 also has a deadening effect on any noise that may be incidental to the discharge of the contents of the bowl.

Fig. 3 shows a simplified form of the helical discharge adapted to the cheaper types of toilet fixtures, dispensing with the more elaborate and concealed trap chamber structure 6, above described. It is preferably formed of an integral length of transparent plastic tubing 12x, bent into the form of a helix with the vertical discharge portion 15x bent downward, either outside or

centrally of the helix, and connected with the sewer pipe 9, as described. The transparent helix permits easy checking of the working conditions of the discharge, in factories and public installations. It is equally adaptable to the concealing housing 18 where outward appearance is a consideration.

Having fully described this invention and its mode of operation what I claim and desire to secure by Letters Patent is:

10. A toilet bowl with a water inlet and a tangential outlet and a trap chamber open to said outlet and having a sewer discharge outlet; and a block sealed in said trap chamber and having a helical groove in its perimeter and a central passage therethrough and connecting with the sewer discharge outlet of said chamber.
15. A toilet having a bowl with a water inlet and outlet, and a trap chamber open to said outlet and having a sewer outlet; and a block within said trap and having a helical groove in its perimeter and a central passage therethrough connecting with said sewer outlet.
20. A toilet bowl with a water inlet and a discharge outlet; a trap chamber open to said bowl outlet and having a sewer discharge outlet; a block sealed in said trap and having a helical groove in its perimeter and a central outlet therethrough connecting with said sewer discharge outlet from said trap chamber; and a removable cover sealing the top of said trap chamber.
25. A toilet bowl with a water inlet and a discharge outlet; a trap chamber having a tangential inlet connected with the outlet from said bowl and having a sewer discharge outlet; a cover sealing the top of said trap chamber; a block sealed in said trap chamber and having a helical passage therein connected with the discharge outlet from
30. 40. said bowl and to the sewer discharge outlet from said chamber; and means for supplying water to said bowl.
